UNITED STATES PATENT OFFICE

HENRY W. ZEMKE, OF MILWAUKEE, WISCONSIN.

COMBINED SAFETY LETTER-SHEET AND ENVELOP.

1,216,762.

Specification of Letters Patent. Patented Feb. 20, 1917.

Application filed April 4, 1911. Serial No. 618,906.

To all whom it may concern:

Be it known that I, HENRY W. ZEMKE, a citizen of the United States, residing at Milwaukee, in the county of Milwaukee and State of Wisconsin, have invented new and useful Improvements in a Combined Safety Letter-Sheet and Envelop or the like, of which the following is a specification.

My invention relates to a combined letter-sheet and envelop, that possesses superior advantages with respect to construction and has for its objects to improve and simplify the methods of its use.

The primary object of my invention is to provide such an article in a more economical manner than the method now in use, as to a saving of material and labor, in cutting, gumming, folding, addressing, sealing and opening.

20 A further object of my invention is to provide a combination form, of the above character, in which matter of any process or description, inclosures, advertising-pages, etc, may be safely enveloped and transmitted from one party to another with one side or end open for postal inspection, without the aid of extraneous fastening devices and without danger of being unintentionally removed or lost therefrom.

30 Another object of my invention is to provide means, whereby the letter-sheet and envelop may be addressed simultaneously, at the time of writing the communication, to avoid the erroneous handling and the frequent mistakes caused by the placing of a letter addressed to one person in an envelop addressed to another; and to provide means to facilitate the removal of the letter-sheet and its inclosures, so that it can be done effectually and quickly without cutting the side or end edges of the envelop; to avoid the danger of tearing the letter-sheet and the obviously unsatisfactory and inconvenient method of squeezing the envelop edge-wise or blowing into same in order to remove the contents.

With the above and other objects in view that will appear as the description proceeds, the invention consists in the novel construction and arrangements of the parts, that I shall hereinafter fully describe and then point out the novel features thereof in the appended claim.

For a full understanding of my invention

and the merits thereof reference is to be had 55 to the following description and accompanying drawings in which:

Figure 1, represents a perspective view of my invention, showing the letter-sheet folded, and flaps unfolded with a row of 60 perforation and an adhesive coating extended along limited inner surface areas of the combined end and side flap. Fig. 2 is a front face view of the envelop, and Fig. 3 a back face view of same showing the end 65 flaps united. Fig. 4 is a perspective view showing the side flap severed and the letter-sheet unfolded, after same is sealed and opened.

Similar letters and figures refer to similar 70 parts throughout the several views.

Referring now more particularly to the drawings, there is shown a combination form of a letter-sheet and envelop, comprising sections 1, 2, 3 and 4, an end flap A, and 75 a combined end and side flap B and B¹, provided with a row of perforations c, and an adhesive coating b, extended along limited inner surface areas.

In practice sections 1, 2, 3 and 4, are bent 80 inwardly along line a¹, and then transversely along line a², to the back face of section 3, thus retaining an inclosure which may be placed between the inner faces of sections 1 and 3, or sections 2 and 4. Thereafter the 85 combined end and side flap B and B¹, is bent along line a³ and folded inwardly over the outer free side edges of said folded sections; so as to permanently unite the inner faces of end flaps A and B, with each other, 90 after which the said end flaps may be bent transversely along line a⁴, as shown in Fig. 3, thus forming an envelop to safely protect the contents yet having one side and end open to simultaneously extract or inclose the 95 letter-sheet and an inclosure. By this folded arrangement the fold lines are dented and the back face of section 1, is exposed to receive an address and a postage stamp.

In postal practice, the sealed end flaps 100 A and B, and outer exposed folded ends of sections 2 and 4, may be gripped and either bent or pulled outward so as to expose the loose edges of said sections, in order to examine the contents and to unfold the letter-sheet; however, the corners opposite the diagonal edge of said side flap B¹, may be gripped and bent similar, in order to obtain 105

equivalent results. The recipient may do likewise or tear off sealed end flaps A and B, along their dented edges.

When the invention is intended to be transmitted sealed, it is made up and operated comparatively the same as first described above with the exception that the inner face of side flap B¹, is then united with the back face of section 2, and that the 10 said side flap B¹, will tear along the row of perforation c, when extracting the letter-sheet, and appear as shown in Fig. 4.

Further when the said letter-sheet and envelop is addressed simultaneously, sections 1, 2, 3 and 4, are folded along line a¹, to the back faces of each other, the addressing being done in this instance on the front face of section 3, of the letter-sheet, and transferred to the back face of section 1, of 20 the envelop with the aid of a carbon paper, between the back faces of sections 1 and 3, at the time of writing the communication, with the full address of the party, that is, date, name, number, street, etc., which enables 25 the dispensing with the full address at the beginning of the letter, yet assures a perfect postal address on the envelop, and thereby providing positive legal proof as to the fact and date of mailing the letter.

30 It is also obvious that the said letter-sheet may be reinforced with advertising or extra pages, which may be united therewith with an adhesive or otherwise.

This combination form, in a letter-sheet 35 and envelop, is adapted for matter of any process or description, and it may be used

for bills, statements, invoices, price-lists, circulars, announcements, invitations, souvenir-post-cards, and for mailing photographs, catalogues or the like, unsealed; and it is 40 to be understood that I do not wish to limit myself to size nor to the number of folding sections herein shown, as it is obvious that a greater or less number may be employed.

I am aware that changes in the form, and 45 details of construction may be made without departing from the general spirit or sacrificing the advantages of my invention, and I, therefore reserve the right to make all 50 such changes as fairly fall within the scope of my invention.

What I claim as my invention is:

The combination and arrangement, in a letter-sheet and envelop, having a plurality 55 of folding sections, one of the sections having an end flap; and a combined end and side flap provided with a row of perforations and an adhesive coating extended along limited inner surface areas; said sections being indented at intervals, to fold said 60 combined flap inwardly, so as to permanently unite the inner faces of said end flaps, thereby providing an envelop having one side and end open, to fold the adjacent sections in or out, for the purpose as specified.

In testimony whereof I affix my signature in presence of two witnesses.

HENRY W. ZEMKE.
